ELECTRIC SIGNAL ENCODER

Paul Mandel, Paris, France, assignor to La Radio-
Industrie S. A., Paris, France, a corporation of
France

Application May 31, 1951, Serial No. 229,049

Claims priority, application France June 14, 1950

10 Claims. (Cl. 340—354)

1

The present invention relates to encoders of electric signals of the kind in which a train of periodic number representing pulses is delivered each time an actuation signal, generally a single electric pulse, is applied on their input. In such encoders, any coded train represents, by presence and absence of concrete pulses in its code elements, the sequence of the coefficients of the arithmetic development of a number expressed in the so-called binary system of numeration, that is the system of numeration having the figure 2 taken as radix. In its general form, such a development is:

$$a_0 + a_1 \cdot 2 + a_2 \cdot 2^2 + \dots + a_{n-1} \cdot 2^{n-1}$$

for the writing of any number between zero and 2^{n-1} . The coefficients $a_0, a_1, a_2, \dots, a_{n-1}$ can only receive one of the two values 0 and 1, and the writing particular to a given number of a value comprised between 0 and 2^{n-1} is obtained by ascertaining an appropriate repartition of said values 0 and 1 to the various coefficients.

The invention related more specifically to encoders of the kind in which all the electrical codes of numbers comprised between zero and 2^{n-1} are present in a circuit arrangement which includes, in its input and (or) its output, means for selectively delivering a coded train of number representing pulses corresponding to an elected value of number when an actuation pulse, of a duration at most equal to the duration of a code element of the train, is applied on its input.

One object of the invention is to provide certain embodiments of such encoders which, being easy to design and adjust, can be operated with a very high rate of code elements when required.

A further object of the invention is to provide said embodiments of encoders such that they can be actuated either in a rhythmic or in an arrhythmic mode of control, whilst always delivering a coded pulse train of rhythmed or recurrent code elements according to whether they are designed for the encoding of initiating pulses applied at random intervals of time on their inputs, said intervals being though always higher than the maximum duration of any coded train to be delivered, or they are designed for the encoding of a series of amplitude-modulated pulses sampled from a permanent amplitude-modulated signal at recurrent intervals equal to or higher than the maximum duration of any coded train to be delivered. When $(n-1)$ is the maximum order of the development above, the maximum duration of such a coded train is $n\theta$, if θ is the individual duration of a code ele-

ment, as a train of $(n-1)$ order has n code elements.

In the following description, for the sake of simplicity, the maximum order $(n-1)$ to be considered will be 2, corresponding to developments of three terms: $a_0 + a_1 \cdot 2 + a_2 \cdot 2^2$, so that the coded pulse trains concerned will have a maximum duration of 3θ , as they present three code elements or moments. Any extension to a higher number of terms or code elements will appear evident by merely adding encoding channels or stages in the described encoders, until the required numerical capacity is reached.

Encoders according to the present invention, and means for actuating same, will be fully described in relation to the attached drawings, in which:

Fig. 1 shows a diagram of electric signals for explaining the operation of said encoders.

Fig. 2 shows the basic circuits of encoders as provided in the invention.

Fig. 3 shows a block schematic arrangement of said basic circuits in which encoding channels are maintained distinct.

Fig. 4 shows a schematic arrangement of a complete circuit for encoding a permanent signal, in which is incorporated the encoder of Fig. 3, and,

Figs. 5 and 6 show two alternative block schematic arrangements derived from the arrangement of Fig. 3 from a contraction of the encoding channels in a single cascade connection of the basic circuit stages.

The above mentioned restriction to three code elements for the trains to be generated, of a maximum duration $T=3\theta$, limits the configuration of the seven code signals to those indicated under references 1 to 7 in Fig. 1. The remaining signal, being zero, is not considered as it comprises merely a total absence of pulse at the three code elements.

These coded signals, from 1 to 7, are generated by encoding a single pulse such as 8, Fig. 1, applied at the input of the encoder, for instance at instants separated in time by the interval T .

The selection of the code to be applied on said pulse 8 may be provided, as it will be described further, either by applying said pulse 8 on a particularized input terminal of the encoder, or by applying said pulse 8 on all inputs but applying then a selection signal of T duration, such as 9, Fig. 1, on a particularized output terminal of the encoder concerned.

An encoder according to the present invention is broadly characterised in that the basic encoding circuit is constituted by electronic rocking or

trigger stages having a single stability condition. Such stages are often called "single shots" or "one-shots" multivibrators in the usual technical literature, and also "monostable trigger stages" which designation will be used throughout the present description. Such monostable trigger stages can be designed as indicated at I and II in Fig. 2. Considering stage I, a double triode tube 10 has one of its grid connected to an input terminal 11 through an input coupling circuit 12-13. 12 is a series capacitor and 13 a biasing resistor. The plate of this triode element is connected to the high voltage direct current supply through a delay line 15 and a resistor 14. The delay line 15 is short-circuited at one end, as indicated at 16. The ground cathode-bias 17 is common to both triode elements. The second triode element has its control grid biased at 18 and connected through the capacitor 19 to the plate of the first triode element. From the plate circuit of said second triode element, is taken, through the capacitor 20, the output conductor 21.

The operation of such a monostable stage, well known per se, may be explained as follows: at rest, the first triode element is on, the second is off. When an incoming signal, of negative polarity is applied at 11, the first triode element is cut-off and the plate impulse of said element, of positive polarity, goes along the delay line 15, is reflected at 16 with reversed polarity and comes back. The second triode element has been put in the on condition by the pulse from the plate of the first, direct through capacitor 19. The reflected pulse, then, when returning to the plate, is applied in its reversed polarity, and its own delay, to the grid of the second element which is put in the off condition again, the first element being then brought to the on condition. The stage has thus rocked twice by the application of a single input pulse, and has thus delivered in the output conductor 21 an electric pulse the duration of which is defined by the transit time to and fro of the delay line 15. A similar result can be obtained by replacing the delay line 15 by a lumped constant RC circuit, though with a lesser precision of stroke. The bias connection may be so made as to obtain an inverted operation, the rest condition of the stage being then given by the off condition of the first triode and the on condition of the second, the actuation pulse and the delivered pulse being then of inverted polarity as to the given example.

The length in time of the output pulse at 21 is then given by the length of delay line 15 from its input to the short-circuit 16 and back. If said length is taken equal to θ , the monostable trigger stage when actuated, will generate a signal such as 1, Fig. 1. If this length is taken equal to 2θ , it will generate a signal such as 3, Fig. 1, and if this length is taken equal to 3θ , it will generate a signal such as 7, Fig. 1. In other words, the "reading" by an incoming pulse, of the value of delay in 15 will cause the generation of coded signals representing the numerical values 1, 3 and 7, according to the magnitude of delay of line 15.

In order to generate signals such as represented at 2, 4 or 6, Fig. 1, featuring the numbers 2, 4 and 6, which signals are characterised by an initial delay before the appearance of a voltage amplitude, it is then provided to connect an additional rocking stage, II, of the same kind, in cascade connection with the first, I. Such a circuit is also shown in Fig. 2. This second stage II will act as a delay circuit if, between its own output 21 and the actuating point 22 of stage I, a differ-

entiating circuit is inserted, constituted for instance by a series condenser 23 and a grounded shunt resistor 24. This circuit differentiates, in the mathematical meaning of the word, the output signal at 21, stage II, that is to say that, from a single pulse such as 1, Fig. 1, let only subsist two sharp pulses, of mutually reversed polarities which define the instants of beginning and ending of pulse 1. The sharp front pulse is clipped by diode 25, plate-biased at 26, so that the coupling capacitor 27 will only pass towards 22 the sharp rear pulse, delayed by θ with respect to the front pulse.

If now, stage II has a delay time of θ , the pulse signal thus generated at the output of stage I is of the shape indicated at 2, Fig. 1. If stage II has a delay time of 2θ , the pulse signal thus generated at the output of stage I has the shape indicated at 4, Fig. 1. In both cases, stage I is provided with a delay time of θ .

If, on the other hand, stage II is provided with a delay time of θ and stage I with a delay time of 2θ , the signal at the output of stage I will be such as indicated at 6, Fig. 1.

If now, stage II is provided with a delay time of 2θ , and stage I with a delay time of θ , the simultaneous application of two pulses on both inputs of the two stages will produce an output signal of the shape of 5, Fig. 1.

The derivation of signals of more complex configurations, corresponding to higher values of numbers may be similarly provided by providing more values of delays and (or) a greater number of monostable stages connected in cascade relation through differentiating circuits.

Having thus defined the basic circuits of encoders according to the present invention, two kinds of embodiments may be provided. In the first, as shown in Fig. 3, a number, here seven, of distinct elementary encoders are distributed in seven channels, from 31 to 37. In the second, as will be shown in relation to Figs. 5 and 6, it will suffice of three monostable rocking stages, by a mere contraction of the elementary encoders of Fig. 3.

In Fig. 3, the body of the encoder proper is comprised between dotted lines 39 and 40. A common input channel for the application of reading pulses is shown at 28 and channels 31 to 37 may be connected by code selection contact means, as indicated at 29, . . . 29, to said input channel 28. These contacts may be cam combining contacts, in an electro-mechanical embodiment, or better, in an all-electronic embodiment, to be further described in relation with Fig. 4, by targets inserted within a cathode ray tube selector.

In alternative, contacts 29 may be omitted or closed and the code selection for the output common channel 30 may be made through output selecting contact means, from 38, to 38, of the same kind as means 29.

In the first case, contacts 29 need to be closed during an interval of time no longer than θ ; in the second, contacts 38 need to be closed each time during an interval of time equal to T.

Channel 31 embodies a single monostable stage 41 of delay time θ , delivering the signal representing the numerical value 1. Channel 32 embodies a monostable stage 42, of delay time θ , followed by a second monostable stage 43 having a delay time θ , thus delivering the signal representing the numerical value 2. Channel 33 embodies a single monostable

stage 43, of delay time 2θ , delivering the signal representing the numerical value 3. Channel 34 embodies a first monostable stage 44 of delay time 2θ , then, through a differentiating circuit 50, a second monostable stage 51 of delay time θ , thus delivering the signal representing the numerical value 4. Channel 35 is divided into two branches, the first embodying a single monostable stage 45 of delay time θ , the second in cascade connection through a differentiating circuit 56, two monostable stages 55 and 57, the stage 55 having a delay time of 2θ and the second a delay time of θ , thus delivering at 58 the signal representing the numerical value 5. Channel 36 embodies a first monostable stage 46 of delay time θ , followed through a differentiating circuit 52, by a monostable stage 53 of delay time 2θ , thus delivering the signal representative of the numerical value 6. Channel 37 embodies a single monostable stage 47 of delay time 3θ , thus delivering the signal representative of the numerical value 7.

An encoder arrangement such as in Fig. 3 is particularly fitted to operate in association with a sampling arrangement for encoding a permanent or continuous signal of variable amplitude, for instance for encoding a video television signal.

Fig. 4 shows such a combination of means. Each channel of the encoder of Fig. 3, the body of which is indicated as a whole at 63 in an illustrative delay representation, is connected, through a causal amplifier stage 62, to a target 29 included in a cathode ray tube 59 the beam of which is controlled by the pulse sampling generator 60, of pulse recurrence T . One deflector circuit of said tube, for instance a single pair of deflecting plates, is driven by an amplitude-modulated continuous signal issuing from an amplifier 61 and being for example, a video television signal picked up at the output of a television camera of any kind.

In such an arrangement, at each instant θ of the period T , Fig. 1, a pulse will be generated on one of the targets 29 according to the instantaneous amplitude level of the video signal and this pulse will pass through the corresponding encoder channel so that it will appear at 30 in the shape of the corresponding coded signal. The cathode ray tube fulfills both functions of measuring the signal strength and connecting the selected channel of the encoder to the input pulse arrangement. In tube 59 is indicated an additional target 64 which is provided for indicating a zero, or less than unity, amplitude level, where no output signal is to be delivered by the encoder.

A single coupling thus exists between each target and each encoding channel. Further, the time constant to establish the signal triggering the input stage of each channel may then be made very small and, obviously, such an arrangement can ensure very high speeds of encoding.

When a greater time constant may be allowed, however, it then becomes of interest to restrict the number of monostable stages used in the encoder. Thus, one can consider embodiments such as in Figs. 5 and 6, in which only three monostable stages, cascade-connected through two intermediary differentiating circuits are only used. These stages are referred as 65, 66 and 67, and their time constant is uniformly taken equal to θ . The differentiating circuits are referred as 68, between stages 65 and 66, and 69 between stages 66 and 67. Stage 67, in Fig. 5 may be, if required or wished, taken with a delay time

lesser than θ , so as to separate pulses more definitely in the output signals.

Referring to Fig. 5, the individual inputs of stages 65, 66 and 67, referred to as 70, 71 and 72 respectively, of an input mixer, shown under the form of a resistor mixer but in which each resistor may be replaced by the discharge path of a vacuum or gas tube. Said input mixer may be entered in by a reading or initiating pulse by each of the seven code selection terminals 31 to 37. Each of said terminals may be connected to a target 29 of a sampling and qualifying cathode ray tube, as in Fig. 4; said tube receiving for instance a facsimile or telephone signal.

The operation of the arrangement of Fig. 5 becomes evident when following the paths from any input terminal to the output conductor 30, with no difference with respect to that of Fig. 3, when contact means 38 are omitted and the code selection operated from contact means 29.

In the alternative arrangement of Fig. 6, the progression of the pulses in the cascade of stages is reversed, a common input channel being provided for the actuation of stage 67, by recurrent pulses. The coded trains of all the numerical values from 1 to 7 are thus generated each time an initiating pulse enters at 69. The output mixer is similarly made as the input mixer of Fig. 5, and its points 71, 78 and 79 are respectively connected to the individual outputs 74, 75 and 76 of stages 67, 66 and 65. The output terminals of the mixer, referred to as 81 to 87, are individually connected to grids of vacuum multi-grid tubes 91 to 97, the plates of which are connected in common to the output conductor 30 of the encoder. These grids may be for instance the control grids of tubes 91 to 97 or they may be conversely suppressor; on other grids of said tubes, suppressors or control grids, are applied selection code pulses at terminals 31 to 37, one selection pulse at a time, of duration T , so that one only of said tubes is placed in the on condition and transmits the coded signal applied at the output terminal of the mixer 73 to which it is related.

The terminals 31 to 37, can here again, be connected to respective targets of a measuring and sampling cathode ray tube.

I claim:

50. 1. In an encoding device for transmitting binary code combination representing numbers from zero to a maximum value 2^{n-1} wherein the maximum duration T of a code combination is $n\theta$, where θ is the duration of an individual code element, the combination of a circuit comprising 2^{n-1} channels, each of said channels including at least one one-shot multivibrator delivering a pulse having a minimum time duration of θ , at least one of said channels including a differentiating circuit connected to the output of its one-shot multivibrator, a limiter device for transmitting only the second sharp pulse produced by said differentiating circuit, and a second one-shot multivibrator included in said one channel and controlled by said limiter device.

60. 2. An encoding device according to claim 1 wherein said channels are connected to a common output circuit, and including means selectively applying to the inputs of said channels actuating pulses separated by the interval T , said actuating pulses being of short duration with respect to said interval.

70. 3. An encoding device according to claim 1 wherein said channels are connected to a common input circuit connected to a source of actua-

ing pulses separated by the interval T and being short relative to said interval, and including means for selectively connecting the outputs of said channels to a common output circuit.

4. In an encoding device for transmitting binary code combination representing numbers from zero to a maximum value 2^{n-1} wherein the maximum duration T of a code combination is $n\theta$, where θ is the duration of an individual code element, the combination of a circuit comprising 2^{n-1} channels, each of said channels including at least one one-shot multivibrator delivering a code pulse having a minimum time duration of θ , certain of said channels including only one multivibrator and delivering pulses having durations which increase progressively by intervals of θ from one channel to another, at least one other channel including a differentiating circuit connected to the output of its multivibrator, a limiter device connected to said differentiating circuit for transmitting only the second sharp pulse produced by the differentiating circuit, and a second one-shot multivibrator controlled by said limiter device.

5. An encoding device according to claim 1 wherein one of said one-shot multivibrators is common to all of said channels.

6. An encoding device according to claim 1 wherein n multivibrators are connected in cascade, the output of each multivibrator in the series being connected with the input of the succeeding vibrator through a differentiating device and a limiting device to transmit only the second sharp pulse generated by the differentiating circuit, and said channels being completed through different combination of said multivibrators.

7. An encoding device according to claim 1 and including a common output circuit for said channels, separate input terminals for said channels, a single deflection cathode ray tube, means for controlling the deflection of the beam of said tube by an amplitude-modulated signal, means for controlling the on-off condition of said beam by a series of recurrent pulses, a series of targets within said tube and spaced along the path of deflection of said beam, said targets being connected respectively to the input terminals of said channels.

8. An encoding device according to claim 1 and including a common input circuit for said channels, means for applying simultaneously initiating pulses on said input circuit, an electron tube on-off switch in the output of each channel, a common output plate connection for said tube switches, a cathode ray tube having a single beam deflection arrangement, means for controlling the deflection of the beam of said tube by an amplitude-modulated signal, means for controlling the on-off condition of said beam by a series of

recurrent pulses, a series of targets within said tube and spaced along the path of deflection of said beam, said targets being connected respectively to the control electrodes of said electron tube switches.

9. An encoding device according to claim 1 wherein said multivibrators are connected in cascade connection through differentiating-clipping circuits, an input mixer having as many output terminals as there are multivibrators in the cascade connection, and having as many input terminals as there exist numbers from 1 to 2^{n-1} , a cathode ray tube having a single beam deflection arrangement, means for controlling the deflection of the beam of said tube by an amplitude-modulated signal, means for controlling the on-off condition of the beam by a series of recurrent pulses, a series of targets within said tube and spaced along the path of deflection of said beam, said targets being connected to the respective terminals of said mixer.

10. An encoding device according to claim 1 wherein said multivibrators are connected in cascade connection through differentiating-clipping inter-stage circuits, means for applying on the input of the first multivibrators a series of recurrent pulses, an output mixer having as many input terminals as there are multivibrators in the cascade connection, and having as many output terminals as there exist numbers from 1 to 2^{n-1} , electron tube switches having each one grid connected to one of said output terminals, a cathode ray tube having a single deflection arrangement, means for controlling the deflection of the beam of said tube by an amplitude-modulated signal, means for controlling the on-off condition of said beam by a series of recurrent pulses, a series of targets within said tubes and spaced along the path of deflection of said beam, said targets being connected each to a second control grid of said electron tube switches, the recurrence of the two series of pulses being the same, the series of input pulses of the cascade connection being of duration lower than the duration of a code element and the duration of beam controlling pulses being equal to the maximum duration of the coded signal corresponding to the 2^{n-1} value.

PAUL MANDEL.
